UNITED STATES PATENT OFFICE.

ORRELL ASHTON, DECEASED, LATE OF SWAMPSMOTT, MASSACHUSETTS, BY HANNAH ASHTON, EXECUTRIX, OF SWAMPSMOTT, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

ASSEMBLING-MACHINE.

1,356,510.

Specification of Letters Patent. Patented Oct. 26, 1920.

Application filed April 17, 1916. Serial No. 91,672.

To all whom it may concern:

Be it known that ORRELL ASHTON, late of Swampscott, in the county of Essex and State of Massachusetts, deceased, invented 5 certain Improvements in Assembling-Machines, of which the following description, in connection with the accompanying drawings, is a specification, like reference characters on the drawings indicating like parts in 10 the several figures.

This invention relates to machines for assembling parts of boots and shoes upon their lasts preliminary to the pulling-over and lasting operations. For the purpose of 15 illustration an embodiment of the invention has been selected and is shown herein as applied to a machine of the type described in Letters Patent of the United States, No. 1,204,928, granted November 14, 1916, upon 20 an application of Orrell Ashton.

It is to be understood, however, that the invention is not restricted to embodiment in a machine of the particular type disclosed in said patent. In the earlier machine above 25 referred to the upper is held to the last at a point adjacent to the heel seat and the upper is wiped downwardly or toward the narrow top part or cone of the inverted last as well as over the heel seat of the last, two tacks 30 being then partially driven into the rear end face of the shoe and a single tack completely driven into the end of the heel seat of the last through the upper material including the heel stiffener or counter which is 35 wiped over the heel seat.

It has been found that improved results are obtained by first securing or holding unyieldingly the upper including preferably 40 the edge of the counter stiffener which is most remote from the last bottom to the rear end face of the cone of the last and then tensioning the upper toward and over the heel seat of the last and there securing the upper materials including the counter to the heel 45 seat. Preferably the upper is also secured to the rear end face of the heel seat at a point near the heel seat.

A feature of the invention consists, therefore, in means for holding the upper materials against the rear end face of the last at 50 a point remote from the last bottom, means

for tensioning the portion of upper lying toward the heel seat from the point held toward and over the heel seat, and means for thereafter securing the upper under tension 55 and preferably to the heel seat of the last. In the construction shown herein the last is bottom up and the upper is held clamped unyieldingly at a point adjacent to the top part of the cone of the last between the last which is pressed inwardly and a block, preferably V-shaped, which is held in fixed position. This clamping means may be relied upon to hold the upper at this point from upward movement relatively to the last. Tacking 60 means, however, is provided for optional use which will insert a tack, preferably through the V-block, additionally to secure the upper to the last, the block being arranged by vertical adjustment to cause the tack to pass 65 through the upper and counter near the edge of the counter which lies nearest the cone of the last. The upper while held at this point, by pressure of the last against the block and also by the tack if desired, is tensioned upwardly by the tensioning means 70 which, as shown herein, comprises the forward end of the wiper and a coöperating gripper member which is actuated to grip the upper between it and the end of the 75 wiper. The wiper is operated in a direction to wipe the upper over upon the heel seat, at the same time acting to tension the upper throughout substantially the full width of the vamp in an upward direction from a 80 point near the top of the cone of the last where it is held by the clamping pressure as described and if desired also by the tack already driven at that point. As the wiper advances the upper, preferably, is gradually 85 withdrawn from between the coöperating gripping surfaces of the wiper and gripper member and is laid under tension upon the heel seat, means being provided for securing the upper materials including the counter 90 thus treated to the heel seat. This means as shown comprises tacking mechanism which acts preferably through the wiper to insert a tack at the rear end of the heel seat through the overlaid margin of the counter, 95 lining and innersole and to clench it upon the heel plate of the last.

The means for clamping the upper unyieldingly against the cone of the last may comprise, as shown, a last support which forces the last rearwardly against the fixed 5 lower V-block and holds the upper clamped at this point during the upward tensioning of the upper. Preferably also the last support is held against downward movement during the overwiping movement of the 10 wiper.

It is important that the shoe support, during the positioning movement of the shoe relatively to the upper tensioning means, be movable vertically to facilitate insertion of 15 the upwardly extending margin of the upper between the gripping members. A feature of the invention, therefore, consists in the combination with tensioning means to which the upper is presented by upward movement 20 of the shoe, of means for supporting the last for depression by light downward pressure and, adapted when the last is released to raise the last and bring the upper into position between the gripping members and the 25 tensioning means.

Another feature of the invention consists in the combination with means for holding the upper unyieldingly at the rear of the last near the cone of the last, and means for 30 tensioning the upper upwardly from the point held, of means for pressing yieldingly against the rear end face of the last at a point adjacent to the heel seat. Means is also provided which may be used when desired for securing the upper to the last at this point by a partially driven tack. As 35 shown, the yielding pressing means comprises a second block which is preferably a V-block and acts to center the last by engagement of its inclined faces with the curved rear face of the last. This block is mounted for yielding movement rearwardly in a substantially horizontal direction, being preferably held forward by a spring 40 45 in a position in advance of the lower V-block so as to engage the shoe first as the shoe is moved toward the machine and to press the shoe parts into assembled relation on the last. As shown tacking mechanism is provided which may or may not be 50 used at the option of the operator to insert a tack preferably through the block and into the rear end face of the shoe at one side of the back seam and near the plane of the 55 heel seat.

In lasting the sides of shoes the side laster is required to see that the ends or wings of the counter stiffener are properly drawn up at the shank of the shoe and 60 secured to the tread face of the shank of the sole. Under some conditions, particularly where molded counters are used, it is also demanded of the side laster that he secure to the heel seat the flange of the 65 counter which extends over the heel seat

at the rear of the shoe by tacks driven not through the upper but through the counter flange and into the heel seat at each side of the tack driven by the assembling machine through the upper and counter flange at the 70 rear portion of the heel seat adjacent to its longitudinal median line. Since the rear portion of the upper is held by this central tack in a position bent over the rear portion of the counter it is only with some difficulty that the laster can insert tacks at each side of the central tack through the flange of the stiffener only and this requirement reduces his production. 75

An important feature of this invention 80 consists in means for inserting tacks through the flange of the counter or heel stiffener automatically and as a part of the assembling operation. By this means tacks are driven near the rear end of the heel seat 85 through the flange of the counter stiffener and into the heel seat. As shown herein the flange tack driving mechanisms operate substantially simultaneously with the means for driving the central tack at the 90 rear end of the heel seat and are located adjacent to what are known as the corners of the heel seat, that is, near the points where the curvature of the rear end of the heel seat merges into the curvature at the side of 95 the heel seat. These flange tacks, therefore, are located at each side of the central tack at the end of the heel seat and somewhat in advance of it or nearer the toe of the shoe. The central tack at the end of the heel seat, 100 herein termed the heel seat tack, is driven through the upper as well as through the counter lining and innersole, and the tacks in advance of it, termed herein the flange tacks, are not driven through the upper but 105 through the flange of the counter stiffener, lining and innersole only, all of these tacks being clenched upon the heel seat plate of the last. Preferably two flange tacks are driven, one at each side of the heel seat 110 tack and in laterally and forwardly spaced relation from it.

Another feature of the invention consists in the combination with the flange tacking means, of means for holding the counter 115 against the last at the corners of the heel seat. The counter is particularly liable to bulge away from the last at the corners of the last and the holding means preferably comprises pressing means acting inwardly 120 locally at points transversely in line with the flange tacking means and substantially in the plane of the heel seat to adjust relatively the counter, upper, and last. The counter pressing means may include pressers 125 which hold in the counter at the wings of the counter and preferably and as shown the corner and wing pressers are so connected to their operating means that the pressure is distributed between them and preferably 130

the upper and lining and innersole assembled thereon, inserts a counter, for example, a molded counter between the upper and lining, and places the last upon the spindle 20. He then depresses the spindle against the spring 18 and swings it toward the machine. Having swung the shoe inwardly as far as it will go, he releases it and allows the post 16 to rise under the impulse of 25 spring 18. This movement brings the upper at the rear of the shoe into the position shown in Fig. 7, the upwardly extending margin of the upper then lying between the nose of a wiper 70 and a gripper member 72 having a gripping face of a curvature corresponding to that of the nose of the wiper and adapted when operated to hold the upper against the nose of the wiper as 30 illustrated in Fig. 8. When the work has been positioned as described the operator depresses a treadle 76, Fig. 1, which acts through a rod 78, Fig. 2, upon a controlling mechanism 79 to connect the shaft 6 with the power driven pulley 80. The controlling 35 mechanism 79 may be of any usual type but as herein shown is substantially similar to that disclosed in United States Letters Patent No. 1,026,067, granted May 14, 1912, on application of Orrell Ashton. As the cam shaft 6 begins to rotate, the projection on the cam 42 passes beyond the roll 40 and permits the spring 44 forcibly to depress the hook 30 which acts upon the roll 50 to draw the jack and shoe inwardly toward the machine and lock it inwardly and against depression as described. As the shoe is drawn in toward the machine it first contacts with an upper V-block 86, Fig. 8. This block is mounted on a horizontal slide 40 to yield inwardly against a spring 88, Fig. 1, and by yielding allows the shoe to come into engagement with a lower V-block 90 which is held in fixed position. The shoe is now held with the upper and counter 45 firmly pressed against the rear end face of the last, the upper being held unyieldingly near the cone of the last at each side of the back seam by pressure of the last against the V-block 90 due to the action of the cam 50 face of the hook 30 upon the last support and being held yieldingly near the heel seat by pressure of the V-block 86. The upwardly projecting portion of the upper has been seized between the nose 70 and the gripper 72 by mechanism actuated simultaneously with the downward movement of the hook 30 in the following manner. Referring to Figs. 3, 4 and 6, it will be seen that the hook 30 when in its normal 60 position with the machine stopped engages a roll 100 on the end of a lever 102 which is pivoted at 104 to a bracket 105 mounted on the base 2. The lever 102 has a projection on its upper face which engages an arm 106 fixed to a rock shaft 108 having also a longer arm 110. The rock shaft 108 tends to rotate in a direction to depress the outer ends of the arms 106, 110 by reason of a spring 111, Fig. 3, coiled about the shaft 108, one end of which engages a lug 70 113 on the bracket 105, the other end of the spring being secured to a collar 115 which is held to the shaft 108 by means of a ratchet and pawl mechanism which affords means for adjusting the tension of 75 the spring 111. A pull rod 112 passes through a trunnion 114 journaled in the outer end of the arm 110 and is connected at its upper end to one arm 116 of a bell-crank lever, the other arm 118 of which 80 is connected by a link 120 to a rod 122 one end of which is rigidly secured to the gripper 72 below its pivot 124. The rod 112 carries below the trunnion 114, an adjustably fixed collar 126, and above the trunnion a sliding collar 128 which is backed by a light spring 130 held by its upper end to a fixed collar 132. Referring now particularly to Fig. 6, it will be seen that when the hook 30 is depressed as described the 85 pressure of the projection on the lever 102 against the arm 106 will be released, permitting the spring 111 to act upon the rock shaft 108 and depress the outer end of the arm 110. This arm acting upon the collar 126 moves downwardly the rod 112 and through the bell-crank lever 116, 118 pulls upon the link 120 to force the gripper member 72 into position to hold the upper between its lower end and the nose 70 of the 90 wiper. When the arm 110 is again forcibly raised at the end of the cycle of the machine the spring 130 will yield if necessary to permit the gripper member 72 to remain closed should its outward movement be interfered with by contact with the work. 95 Mechanism is also provided for holding the counter firmly clamped against the sides of the rear portion of the shoe at the corners of the heel seat and at the wings or end portions of the counter, the pressure being localized particularly upon the upper lateral edges of the shoe bottom. Pressure at these points prevents the counter from bulging or drawing away from the last. This mechanism is actuated simultaneously with the operation of the gripper 72 and comprises mechanism best shown in Fig. 3. The clamping members 150 are located one upon each side of the shoe and each carries two 100 upper clamping projections 152, 154 which are inclined upwardly and inwardly toward the shoe and engage the sides of the shoe in substantially the plane of the heel seat as shown in Fig. 14, the projections 105 154 engaging the shoe at the corners of the heel seat and the projections 152 pressing in the wings of the counter. The members 150 are pivoted for limited movement at 110 156 to arms 158 which are fixed to verti- 115 130

unequally, the greater pressure being applied at the corners of the counter. The presser operating means is automatic in action and comes into operation when the machine starts to press in the counter at the opposite sides of the shoe at the corners and wings of the counter before the flange tacks are driven.

These and other features of the invention 10 will appear more fully from the following description when read in connection with the accompanying drawings and will be pointed out in the appended claims.

In the drawings,

15 Figure 1 is a side view of a machine embodying this invention;

Fig. 2 is a front view of the upper portion of the machine, the jack mechanism being omitted;

20 Fig. 3 is a detail in perspective of the gripper mechanism and the counter pressing and securing mechanism;

Figs. 4 and 5 are sectional details of a portion of the counter pressing mechanism;

25 Fig. 6 is a detail perspective of the gripper mechanism;

Figs. 7, 8 and 9 are diagrammatic sectional views showing the work, gripper mechanism, and rear end tacking mechanism in 30 successive positions;

Fig. 10 is a detail of the tack retaining mechanism in the wiper;

Fig. 11 is a perspective view of the gripper mechanism and counter pressing mechanism;

Figs. 12 and 13 are perspective details of the counter flange tacking mechanism;

Fig. 14 is a detail, partly in section, of the flange tacking mechanism, showing the 40 work;

Fig. 15 is a detail of the cam which operates the pressers for inserting tacks in the rear end of the shoe; and

Fig. 16 is a perspective detail of the rear 45 end of a shoe after the operation of the machine upon it.

Referring to Fig. 1 of the drawing, the numeral 2 indicates the base or column of the machine and 4 the frame of the head of 50 the machine upon which various operating parts of the machine are mounted and are operated by cams or other mechanism connected with the main shaft 6. A jack member 8 is pivoted at 9 to the frame of the 55 machine and has its outward movement limited by a rod 10 carrying a buffer-spring 12. A rod 14 telescopes into the lower end of a jack post 16, the jack post 16 being supported upon the rod 14 by a spring 18. 60 The rod 14 is reduced at its lower end to engage a hole in a piece 15 which is adjustably held in the member 8 by a set screw 17. In the upper end of the post 16 a last pin 20 is fitted which may be adjusted vertically 65 relatively to the post 16 by lifting and rotat-

ing the pin to cause a projection 22 to engage in one of a series of vertically spaced notches 24 formed around the periphery of the upper end of the hollow post 16. The strength of the spring is such that the post 70 may be depressed by the operator, its movement being suitably limited by a pin and slot connection between the parts 14, 16 at 19 and mechanism is provided for forcing and holding the post in toward the machine 75 and for locking it against depression while the machine is in operation. This mechanism comprises a hook 30 pivoted at 32 to the machine frame and arranged to be operated by a rod 34 which connects a rearward 80 extension of the hook 30 with a bell-crank lever 36. The lever 36 is pivoted to the frame 4 at 38 and carries a roll 40 which is acted upon by a cam 42 fixed upon the shaft 6. The action of the cam upon the cam roll 85 40 raises the hook into the position shown against a stiff spring 44 coiled about the axis 32 and arranged forcibly to depress the hook 30 when the projection on the cam 42 moves off the roll 40. When the post is 90 swung toward the machine about the pivot 9, a roll 50 mounted on the member 8 is brought into position to be engaged by the hook 30 when it is depressed, as described, the hook thereby locking the shoe support 95 inwardly toward the machine during its operation. The face of the hook 30 which engages the roll 50 is not concentric with the pivot 32 but is cam-shaped to force the roll and support inwardly as the hook is moved 100 downwardly.

The hook 30 also effects a locking of the post 16 against depression, as shown in Fig. 5. The post 16 has formed upon it a series of ratchet teeth 52 and passes loosely 105 through an opening 53 in a member 54 which is pivoted at 56 to the member 8. The member 54 carries a locking pawl 58 which is arranged to engage the teeth 52 when the member 54 is moved to the left in Fig. 5 by the 110 action of the hook 30 upon the roll 50 provided the post 16 is prevented from moving inwardly by reason of contact of the work with parts of the machine. When movement of the post 16 toward the machine 115 is thus prevented the lower part of the member 54 where the post passes through the hole 53, is, of course, prevented from moving inwardly and the member 54, being held at 53, swings about the pivot 56 causing a projection 60 upon the member 54 to press downwardly upon a spring plunger 62. This movement allows the pawl 58 to come in contact with the ratchet teeth 52 and to lock the post 16 against depression. When the hook 30 is raised the spring plunger 62 acts to release the locking pawl from the ratchet teeth and the post 16 is free to move 120 vertically.

The operator, having taken a last with 125

cal rock shafts 160 mounted in upwardly extending cylindrical portions of the bracket 105. The pivots 156 are preferably at the rear of the centers of the members 150 so that the members constitute levers having unequal arms. The members 150 are held normally turned to one limit of their pivotal movement by spring plungers 162 best shown in Fig. 11 which engage shoulders formed 10 on the members 150 and prevent the members 150 from flopping about when the machine is operated with no shoe in it. The plungers allow the members 150 to yield about their pivots 156 after the projections 152 engage the shoe until the projections 154 come into engagement with the shoe whereupon they both bear upon the shoe and the projections 154, being upon the shorter arms of the levers 150, press with greater 15 leverage against the work at the corners of the heel seat and prevent bulging of the counter at these points. The rock shafts 160 extend downwardly and carry at their lower ends inwardly projecting arms 164. Coiled 20 torsion springs 166 are connected between the bracket 105 and fixed collars 167 on the rock shafts 160 so as to cause the arms 158 to move toward each other thereby bringing the projections 152, 154 on the levers 150 into clamping engagement with the sides 25 of the shoe. When the machine is in stopped position the arms 158 are held separated by the action of an upward extension 168 upon the lever 102 which then engages the ends of the arms 164, as shown in Fig. 3. When the hook 30 descends, however, the lever 102 is released and the projection 168 is moved rearwardly by the action of the springs 166 which cause the members 150 30 to come into clamping engagement with the work simultaneously with the operation of the gripper member 72 to seize the upper. The upper is now correctly positioned and held for the insertion of the first fastening 35 which is inserted through the lower V-block 90, as shown in Fig. 8. The tack for the block 90 is supplied by a tack separator located at 170, Fig. 1, and passes through a tube 172 into a driver passage in the block 40 90 in front of a driver mounted on a driver bar 174 which is actuated by a lever 176 pivoted at 178 and having a projection 180 which engages a cam 182 on the main shaft. The drop of the cam is so arranged as to 45 actuate this driver by its driver spring mounted upon the shaft 178 prior to the actuation of the other tack drivers and prior to the forward reciprocation of the wiper 70 which next takes place. 50 The wiper 70 is mounted and operated in a manner substantially as is shown and described in the patent first referred to above. It is therefore not necessary to describe this construction in detail. The wiper 70 is 55 moved forwardly over and along the me- dian line of the rear part of the heel seat of the shoe and in its movement assumes successively positions shown clearly in Figs. 7, 8 and 9. During this movement the gripper member 72 holds the upper against 60 the end of the wiper 70 and coöperates therewith to tension upwardly at the rear of the shoe the portion of the upper which extends above the tack already driven through the block 90. At this point the upper is held 65 by said tack and by the pressure of the shoe against the rigidly held block 90 while the upper block 86 is held yieldingly against the upper and permits the upper to draw upwardly beneath it as the wiper and gripper member advance to tension the upper over the shoe bottom. During this movement the portion of the upper held between the nose of the wiper and the gripper member is gradually withdrawn from engagement between them. While held under tension by the frictional engagement of these members, however, it is laid down upon the shoe bottom and is held in that position by pressure of the wiper on the shoe bottom 70 until it is secured by a tack driven through the wiper 70 and into and through the overlaid upper, counter, lining and innersole and clenched upon the heel plate of the last, as 75 is clearly shown in Fig. 9. 80 The wiper 70 moves a predetermined distance over the shoe bottom and hence the heel seat tack is driven at a predetermined distance from the rear edge of the bottom of a shoe positioned by the block 90. This distance may be varied by turning the hand wheel 85, the construction for effecting this adjustment being substantially the same as that shown and described in the prior patent 85 first referred to above. 90 The wiper 70 is let into the upper face of the block 86 by a groove 71, Fig. 3. This construction permits the upper block 86 and its tacking mechanism to be adjusted near to the plane of the heel seat. 100 Substantially simultaneously with the insertion of the tack in the heel seat, as just described, a tack is inserted through the upper V-block 86 into the rear end face of the last at a point at one side of the back 105 seam and adjacent to the plane of the heel seat, as is also clearly shown in Fig. 9. This tack and the lower tack previously driven are preferably left with their heads upstanding from the surface of the upper to facilitate their subsequent withdrawal. The upper rear tack is supplied by the separating mechanism 170 to the block 86 through a tube 190 and is driven by a driver attached 110 to the forward end of a driver bar 192 which is actuated by a lever 194. The lever 194 is moved to the left in Fig. 1 to tension a suitable driver spring located on the shaft 178 by the action of a cam 196 upon an inward projection 195, Fig. 15, of the lever 194. 115 120 125 130

The cam 196 has its drop so located as to permit operation of the driver bar 192 at a point later in the cycle of the machine than the cam 182 permits operation of the driver bar 174.

For driving the rear heel seat tack a lever 200 is pivoted at 202 to the carrier which advances the wiper 70 over the shoe bottom and is raised to tension the driver spring by 10 the action of a cam 204 located behind the cam 42 in Fig. 1 which acts upon a roll 206 on the lever 200 to raise a driver bar 208. The driver bar 208 is released to drive the heel seat tack, as shown in Fig. 9, substantially simultaneously with or slightly later than the release of the driver bar 192 to drive the upper rear tack, also shown in that figure. The rear heel seat tack is supplied to the wiper 70 by the separating mechanism 170 through a tube 210, Fig. 2, and drops into a tack retaining means in the wiper 70 into position beneath the driver on the bar 208, as shown in Fig. 7. The tack retaining means in the wiper 70 has the construction shown in Figs. 7, 10, and 11, and comprises a member 212 having a funnel-shaped slot 214 open on the inner side and having its wide end located beneath a passage in the wiper 70 leading from the opening of the tube 210 to permit a tack to drop into it. The member 212 has an outwardly extending stem 216 which passes through a member 220 and is retained by a pin 222. A spring 224 is located in a socket in the member 220 and acts to press the member 212 inwardly into tack retaining position but is adapted to yield upon descent of the driver to permit the tack to be driven past the member 212 and into the work. The member 40 220 is formed, as best shown in Fig. 10, with a flange 226 which engages grooves 227 in a wiper member 70 to retain the member 220 in position. The flange 226 is cut away on opposite sides so that by giving the member 45 220 a quarter turn it may be removed from the wiper member 70 for inspection and clearance of the tack passage in case it should become clogged. To insure exact location of the member 212 with the tack 50 passages in the member 70 a locating pin 228 is provided which engages a hole 230 in the member 70 when the member 212 is placed in operative position.

Mechanism is provided for inserting a 55 plurality of tacks through the flange of the counter adjacent to the corners of the heel seat as is clearly shown in Fig. 16. These tacks preferably and as shown do not pass through the upper but through the counter, 60 lining and innersole only and serve firmly to secure the counter in proper position against the rear portion of the last while it is still held in that position by the pressure of the upper V-block 86, by the counter corner and side clamping projections 154, 152,

and by the wiper 70. These flange tacks are supplied by the separating mechanism 170 through tubes 250, 252 to corresponding driver guides 254, 256 located one upon each side of the wiper member 70, as best shown in Figs. 11 and 14. Upon the lower end of each of the guides 254, 256 is provided a tack pocket for holding the tack in position until it is driven comprising two members 258, 259 which are pivoted together by links 260 to 70 permit separation of their tack holding ends and are normally held closed by a spring 262. Between the members 258, 259 is provided a slot 264 and by separating the tack holding ends or jaws of the members 258, 259 these 75 members may be placed in position to be retained upon the lower ends of either of the driver guides 156, 154 which are each formed, as shown, at the right in Fig. 12. When the members 258, 259 are allowed to close, the 80 slot 254 embraces, for instance, the portion 266 of the driver guide 254 and the jaw members are held from downward movement by a flange 268. When thus positioned the tack pocket 270 formed in the inner ends of the 85 members 258, 259 is in alignment with the driver passage 272 in the driver guide 256. The tack pocket 270 has a form half of which is illustrated in Fig. 13 which is adapted to hold a tack in position beneath the driver 90 until its descent whereupon the two portions of the tack pocket yield laterally to permit the passage of the driver through the pocket for the insertion of the tack into the work. It will be observed that by the construction 100 described the tack pockets are readily removable when necessary and for convenience in initially separating the members 258, 259 the forward inner edges of the members are beveled at 274 to permit an implement to be 105 readily inserted either to clear the tack pocket 270 if it become clogged or to assist in separating the members 258, 259 for complete removal of them from the driver guide. The flange tacks are driven by drivers 110 276, 278 which are connected, as shown in Fig. 2, with a head 280 fixed upon the upper end of the driver bar 208 by which the central heel seat tack is driven. By this construction, therefore, the flange tacks are driven simultaneously with the central tack and by the same driver spring. It will be seen that, as shown in Fig. 1, the counter driver guides and drivers are located somewhat in advance of the central heel seat tack so that they pass 115 beyond the portion of the margin of the upper which is laid over the heel seat by the wiper 70 and insert their tacks through the flange of the counter adjacent to the corners of the heel seat and beyond the margin of 120 the upper. The position of the counter tacks is clearly illustrated in Fig. 16. This figure shows also the position of the three other tacks which are driven through the assembled upper.

The counter tack driver guides are arranged for adjustment laterally of the shoe to position the tacks at different points laterally of the flange of either wide or narrow 5 shoes. To effect this adjustment the driver guides 254, 256, Fig. 3, are supported on slotted brackets 255 by screws 257 which pass through the slots in the brackets and into the guides. By loosening the screws 257 the 10 guides may be adjusted in the direction of the slots laterally of the heel seat.

The brackets 255 have forward projections, Fig. 3, on each side of the gripper member 72 to guide its movements. The 15 projections are provided with holes 320 so that a pin 322 may be placed in the position shown to limit outward movement of the gripper 72 or may be placed on the inner side of the gripper in the other holes 320 to prevent 20 closing movement of the gripper when its operation is not desired.

In case it should become desirable when operating upon certain classes of work to discontinue the use of either the flange tacks 25 or the central heel seat tack, mechanism is provided for that purpose. At the upper 30 ends of the tubes supplying these tacks and adjacent to the separator mechanism are provided blocks 300, Fig. 2, which are held in place by a removable pin 302. These blocks at their inner ends are grooved to form a portion of the tack passage and at their outer ends are provided with narrow 35 projections 304. By removing any one of these blocks and inserting it the other end to, the projection 304 will push back the tacks in the corresponding raceway and prevent their being delivered by the separating mechanism to the corresponding tack conducting tube.

40 In Figs. 1 and 2 a handle 306 is shown, by turning which a clamp screw may be loosened to permit adjustment of the lower V-block 90 vertically to permit the insertion of the lower rear tack in various positions 45 vertically of the rear portion of a shoe of any size. In case it is desired to adjust both of the V-blocks 86, 90 together while maintaining their spaced relation, the lever 308, Fig. 2, is operated to loosen a clamp screw 50 and the hand wheel 310 may be turned to adjust both the V-blocks vertically, this construction being substantially as shown in the prior patent first above referred to. To dis- 55 continue the use of the lower tack driven through the block 90, a lever 330, Fig. 1, is thrown forward to bring an arm 336 of the lever behind an upward projection from the driver lever 176 and prevent operation of the lever. At the same time a push rod 332 60 is thrust forward against the tack stop mechanism 334 which is thereby operated to prevent tacks from being fed to the driver until it is again permitted to operate by re- 65 verse movement of the lever 330. Similar mechanism is provided for discontinuing

the driving of the tack through the upper V-block 86.

While the operation of the machine has been given in connection with the description it may be helpful briefly to recapitulate. It is to be understood, however, that while the machine is described as operating upon a shoe having a molded counter, the invention in many of its aspects is equally applicable to machines for use in operating 70 upon shoes having unmolded counters. In the operation of the machine an inverted last having an innersole and an upper including a molded counter arranged thereon is placed upon the spindle 20. The spindle 80 20 and post 16 are then depressed and swung inwardly with the last until the rear end face of the last comes into contact with the block 86. The last is then allowed to be raised by the spring 18 to bring the margin 85 of the upper extending above the last bottom into position between the gripping members 70, 72. The operator then presses upon the shoe to move the block 86 rearwardly and allow the block 90 to come into 90 bearing upon the rear end face of the last near the cone of the last. The blocks act because of their V-shaped formation to center the last and to press and hold the upper in assembled relation to the last by pressure 95 applied on opposite sides of the back seam. The treadle is now depressed to set the clutch 79. The hook 30 first drops under the impulse of the spring 44, locking the jack from downward movement and holding 100 the last firmly in against the fixed lower block 90. At the same time the side pressers 152, 154 are released and press inwardly 105 against the sides of the last. The gripper member 72 is also allowed to operate and 110 grips the upper against the nose of the wiper 70. The cam 182 now permits the driver of the lower tack block 90 to be operated to insert a tack in the rear end face of the last near the top of the last cone. 115 The wiper 70 and gripper member 72 begin now to advance and tension the upper upwardly from the block 90 and over the heel seat. Finally the cams 196, 204 allow the other drivers to be operated by their driving 120 springs and a tack is driven into the rear end face of the last adjacent to the heel seat and another tack is driven at the rear end of the heel seat through the upper and counter flange and into the heel seat. Simultaneously two other tacks are driven in 125 advance of the heel seat tack through the flange of the counter without passing through the outer thickness of the upper. Before the machine stops the hook 30 is raised by the cam 42 to restore the gripper member 70 and the side pressers to their open positions and to unlock the jack so that it may swing outwardly to permit removal 130 of the shoe.

Having fully described my invention, what I claim as new and desire to secure by United States Letters Patent is:—

1. A machine for securing parts of boots or shoes in assembled relation upon a last preliminary to lasting, having, in combination, means for holding the upper and last in assembled relation by vertically localized pressure on the rear end face of the last adjacent to the top of the cone of the last, means for seizing and tensioning the upper from the point held toward and over the heel seat of the last, and means for securing the upper under tension to the heel seat.
2. A machine for securing parts of boots or shoes in assembled relation upon a last preliminary to lasting, having, in combination, means for holding the upper and last in assembled relation by pressure which is vertically localized on the rear end face of the last so as to leave substantially the whole width of the vamp free to be tensioned, means for seizing and tensioning the upper from the point held toward and over the heel seat of the last, means for securing the upper under tension to the heel seat, and means for securing the upper to the rear end face of the last.
3. A machine for securing parts of boots or shoes in assembled relation upon a last preliminary to lasting, having, in combination, means for holding the upper and last in assembled relation by pressure on the rear end face of the last near the cone of the last, means for tensioning the upper from the point held toward and over the heel seat of the last, and means for securing the flange of the counter to the heel seat by fastenings which do not hold the outer thickness of the upper.
4. A machine for securing parts of boots or shoes in assembled relation upon a last preliminary to lasting, having, in combination, means for holding the upper and last in assembled relation by vertically localized pressure on the rear end face of the last adjacent to the top edge of the vamp, grippers for tensioning the upper from the point held toward and over the heel seat of the last, and means for securing the upper and counter to the rear end face of the last and the upper and flange of the counter to the heel seat.
5. A machine for securing parts of boots or shoes in assembled relation upon a last preliminary to lasting, having, in combination, means for holding the upper and last in assembled relation by pressure on the rear end face of the last near the top of the last cone, means for tensioning the upper from the point held toward and over the heel seat of the last, means for securing the flange of the counter to the heel seat by tacks which pass through the counter, lining

and innersole leaving the outer thickness of 85 the upper free.

6. A machine for securing parts of boots or shoes in assembled relation upon a last preliminary to lasting, having, in combination, means for holding the upper and last in assembled relation by pressure on the rear end face of the last near the flat face of the cone of the last, means for tensioning the upper from the point held toward and over the heel seat of the last, means for securing the flange of the counter to the heel seat, and means for further tacking the counter flange by tacks which pass through the counter, lining and innersole only.

7. A machine for assembling upon a last 80 a loosely arranged upper, a counter, and an innersole preliminary to lasting, having, in combination, means for holding the upper unyieldingly pressed against the cone of the last including means for holding the last to secure such pressure, means for seizing and tensioning the upper upwardly from the unyieldingly held portion toward the heel seat, and means for securing the upper while 85 under tension to the heel seat.

8. A machine for assembling upon a last 90 an upper, a molded counter and an innersole preliminary to lasting, having, in combination, means for holding the upper unyieldingly pressed against the cone of the last, yielding means for holding the upper to the rear face of the last adjacent to the heel seat, means for tensioning the upper upwardly from the unyieldingly held portion and beneath the yielding means, means for securing the upper while under tension to the heel seat, means for further securing the counter only to the heel seat, and means for inserting a tack in the rear end face of the last adjacent to the heel seat.

9. A machine for assembling an innersole 95 and the parts of a shoe upper upon a last preliminary to lasting, having, in combination, means for unyieldingly holding the upper and counter against the last at a point remote from the heel seat, means for inserting a tack through the unyieldingly held portion, yielding means for pressing the upper against the rear end face of the last adjacent to the heel seat, means for tensioning the upper upwardly from the unyieldingly held portion, means for securing the upper while under tension to the heel seat, and means for inserting a tack in the rear 100 end face of the shoe adjacent to the heel seat.

10. A machine of the class described having, in combination, a movable last support, a fixed rest arranged to be engaged by the 105 end of the last sustained on said support at a point remote from the heel seat, a yielding mounted rest arranged to be en-

- gaged by the end of the last at a point adjacent to the heel seat, means for tensioning the upper from the fixed rest upwardly and under the yielding rest, means for securing the upper to the heel seat, and fastening inserting mechanism arranged to operate through the yielding rest to drive a fastening into the last. 65
11. A machine of the class described having, in combination, a movable last support, a fixed rest arranged to be engaged by the end of a last sustained on said support at a point remote from the heel seat, a yieldingly mounted rest arranged to be engaged by the end of the last at a point adjacent to the heel seat, means for tensioning the portion of the upper above the fixed rest upwardly, and fastening inserting mechanism arranged to secure the upper to the last at a point adjacent to the yielding rest. 70
12. An assembling machine having, in combination, a depressible last support arranged for movement into and out of operative position substantially in the direction of the length of the last, an unyielding member arranged for engagement with the rear end face of the cone of the last, means for forcing the last support against said member to hold the upper unyieldingly between the last and said member, means for tensioning the upper over the heel seat of the last, means for holding the support against depression, means for wiping the upper over the heel seat of the last, and means for securing the upper to the heel seat. 75
13. A machine for securing in assembled relation upon a last an upper, counter, and innersole, having, in combination, a resiliently supported last support arranged for movement longitudinally of the last supported thereon for presentation of the shoe parts to the machine, a gripper mechanism to which the upwardly projecting margin of the upper at the rear of the last is presented by depressing the last on its support, moving it longitudinally beneath the gripper and releasing it, a fixed rest to bear upon the rear face of the shoe adjacent to the cone of the last, means for operating the last support to clamp the upper against the rest, means for operating the gripper mechanism to seize and tension the upper from the rest upwardly, and means for securing the tensioned upper in place. 80
14. A machine for securing in assembled relation upon a last an upper, counter, and innersole, having, in combination, a resiliently supported last support arranged for movement longitudinally of the last supported thereon for presentation of the shoe parts to the machine, a gripper mechanism to which the upwardly projecting margin of the upper at the rear of the last is presented by depressing the last on its support, moving it longitudinally beneath the gripper and releasing it, a fixed rest to bear upon the rear face of the shoe adjacent to the cone of the last, means for operating the last support to clamp the upper against the rest, means for operating the gripper mechanism to seize and tension the upper from the rest upwardly, and means for securing the tensioned upper in place. 85
15. A machine for securing in assembled relation an upper, counter and innersole upon a last preliminary to lasting, having, in combination, means for securing the upper and counter to the rear end face of the last adjacent to the edge of the counter which is most distant from the bottom of the last, means for thereafter tensioning the upper upwardly and wiping it over the heel seat of the last, and means for securing the upper in wiped over position. 90
16. A machine for securing in assembled relation an upper, counter and innersole upon a last preliminary to lasting, having, in combination, means for securing the upper and counter to the rear end face of the last adjacent to the edge of the counter which is most distant from the bottom of the last, means for tensioning the upper upwardly and wiping it over the heel seat of the last, means for securing the upper in wiped over position, and means for securing the upper and counter to the rear end face of the last near the heel seat. 95
17. A machine for assembling, preliminary to lasting, an upper, counter and innersole loosely arranged upon a last, having, in combination, mechanism for driving a tack through the rear end face of the upper arranged upon the last, gripping means operating after the tack is driven for seizing and tensioning the upper which lies above the driven tack over the heel seat, and means for securing the upper to the heel seat. 100
18. A machine for securing parts of boots and shoes in assembled relation preliminary to lasting, having, in combination, means for securing the upper to the rear end face of the last at a point remote from the rear edge of an innersole sustained upon the last, means for thereafter seizing and tensioning the upper upwardly over the rear edge of the innersole, means for bringing said securing means and tensioning means successively into operation, and means for securing the tensioned upper to the innersole. 110
19. A machine for securing parts of boots and shoes in assembled relation preliminary to lasting, having, in combination, means for securing the upper to the rear end of the last at a point remote from the heel seat, a gripper for tensioning the upper upwardly over the heel seat, means for thereafter se- 115
- 120
- 125

curing the upper to the heel seat, and means for bringing said securing means successively into operation.

20. A machine for securing parts of boots and shoes in assembled relation preliminary to lasting, having, in combination, means for securing the upper to the rear end face of the last at a point remote from the rear end face of an innersole sustained upon the last,
- 10 a gripper for seizing and tensioning the upper upwardly over the rear edge of the innersole, means for bringing said securing means and gripper successively into operation, and means for securing the tensioned upper to the innersole.

21. A machine for assembling an upper, a counter and a sole upon a last, having, in combination, means for securing the upper and counter to the rear end face of the last,
- 20 and means for securing the counter only to the sole at a plurality of points.

22. A machine for assembling an upper, counter and innersole upon a last preliminary to lasting, having, in combination,
- 25 means for holding said shoe parts in assembled relation, and means acting automatically first to secure the upper and counter to the rear end face of the last and then to secure the counter to the heel seat at
- 30 a plurality of points.

23. A machine for securing in assembled relation upon a last an upper, counter and innersole loosely arranged thereon, having, in combination, means for securing the upper and counter to the rear end face of the last at a plurality of points, and means for securing the counter to the heel seat at a plurality of points.

24. A machine for securing parts of boots and shoes in assembled relation on a last preliminary to lasting, having, in combination, means for automatically pressing a molded counter mounted loosely upon the last into close relation to the end of an innersole arranged upon the last, fastening inserting means movable over the last to secure the counter flange at the rear end of the heel seat, and fastening inserting means movable lengthwise of the shoe for securing the counter flange to the heel seat at additional points.

25. A machine for securing in assembled relation an upper, molded counter and innersole loosely arranged upon a last, having, in combination, means for holding the counter from bulging outwardly at the corners of the last, and means for tacking the flange of the counter only to hold it in place.

- 60 26. A machine for securing in assembled relation an upper, molded counter and innersole loosely arranged upon a last, having, in combination, means for pressing in the counter at the corners of the heel seat, and

means for tacking to the heel seat the flange of the counter only.

27. A machine for securing in assembled relation an upper, molded counter and innersole loosely arranged upon a last, having, in combination, means out of contact with the shoe while the upper is being positioned relatively to the last and operating when the machine starts to press inwardly the counter at the corners of the heel seat, and means for simultaneously tacking the flange of the counter to the heel seat at points adjacent to the corners of the heel seat.

28. A machine for securing in assembled relation an upper, molded counter and innersole loosely arranged upon a last, having, in combination, means operating only after the machine starts to apply pressure at the corners of the heel seat simultaneously in directions substantially parallel to the heel seat, and means for tacking the flange of the counter to the heel seat adjacent to the corners of the heel seat.

29. A machine for securing in assembled relation an upper, molded counter and innersole upon a last preliminary to lasting, having, in combination, means for applying pressure inwardly at the corners of the heel seat substantially in the plane of the heel seat, and means for tacking the flange only of the counter to the heel seat at points adjacent to the corners of the heel seat.

30. A machine for securing in assembled relation an upper, molded counter and innersole upon a last preliminary to lasting, having, in combination, means for pressing inwardly the flanged counter at the corners of the rear portion of the last and at the wings of the counter, and means for tacking the flange only of the counter to the heel seat.

31. A machine for securing in assembled relation an upper, molded counter and innersole upon a last preliminary to lasting, having, in combination, means for pressing inwardly the flange counter at the corners of the rear portion of the last and at the ends of the counter constructed and arranged to apply greater inward pressure at the corners of the counter than at the end of the counter, and means for tacking the flange of the counter to the heel seat.

32. A machine for securing in assembled relation an upper, molded counter and innersole upon a last preliminary to lasting, having, in combination, means for holding in the molded counter at the corners of the last and at the wings of the counter by pressure localized at points substantially in the plane of the heel seat, and means for tacking the flange only of the counter to the heel seat to prevent the counter from bulging away from the corners of the last.

33. A machine for securing in assembled

relation an upper, molded counter and innersole upon a last preliminary to lasting, having, in combination, means for pressing the upper materials including the molded counter against the sides of the last at the corners of the heel seat and at the ends of the counter wings, means for wiping over the upper at the rear end of the heel seat, means for securing the upper to the heel seat, and means for inserting fastenings through the flange of the counter only adjacent to the corners of the heel seat.

34. A machine for securing in assembled relation an upper, molded counter and innersole loosely arranged upon a last preliminary to lasting, having, in combination, means acting locally substantially in the plane of the last bottom for holding the shoe upper materials including the molded counter against the sides of the last at the corners of the heel seat, means for pressing in the counter against the last at the corners of the last, and means for securing the counter to the heel seat of the last to hold it in place at the corners of the last.

35. A machine for securing in assembled relation an upper, molded counter and innersole upon a last preliminary to lasting, having, in combination, means for pressing the upper materials including the molded counter against the sides of the last at the corners of the heel seat, means for securing the upper and counter to the heel seat at the rear end of the heel seat, and means for inserting fastenings through the flange of the counter adjacent to the corners of the heel seat but not through the outer layer of the upper.

36. A machine for securing in assembled relation an upper, molded counter and innersole upon a last preliminary to lasting, having, in combination, means for pressing the shoe upper including the molded counter against the last at the corners of the heel seat, means for pressing the counter against the last at the rear of the shoe, and means for securing the counter only adjacent to the corners of the heel seat in the position in which it is held by the pressing means.

37. A machine for securing parts of boots and shoes in assembled relation preliminary to lasting, having, in combination, means for automatically pressing a counter mounted loosely upon a last in close relation to the end of the innersole arranged upon the last, means constructed and arranged for securing the counter to the innersole at predetermined distances from the edge of the last and at a plurality of points, and means arranged for adjustment to vary the distance of the points so secured from the edge of the last.

38. A machine for securing parts of boots

and shoes in assembled relation preliminary to lasting, having in combination, means for automatically pressing a molded counter mounted upon a last into close relation to the end of an innersole arranged upon the last, means constructed and arranged for securing the counter and upper to the innersole at the rear end of the heel seat, and means for simultaneously securing the counter flange only to the heel seat at a plurality of other points.

39. A machine for securing parts of boots and shoes in assembled relation preliminary to lasting, having, in combination, means for pressing an upper and molded counter into assembled relation upon the last, means for securing the counter flange only to the heel seat at opposite sides of the heel seat, and means constructed and arranged to permit adjustment of the securing means laterally of the heel seat.

40. A machine for securing in assembled relation an upper, counter and innersole upon a last preliminary to lasting, having, in combination, means for holding in the counter at the sides of the heel portion by pressure applied locally to the shoe at separated points substantially along the sole edge, means for holding the counter against the rear end of the last by pressure applied longitudinally of the last, means for wiping the upper over the counter and innersole, and means for securing the counter margin to the innersole at a point at the center of the rear end of the heel seat and at single points one at each side of said central point.

41. A machine for assembling an upper, a molded counter and an innersole on a last preliminary to lasting, having, in combination, means operating only after the machine starts to apply pressure to the sides of the shoe adjacent to the corners and wings of the counter, and means for securing the flange of the counter to the innersole adjacent to points of application of said pressure.

42. A machine for assembling an upper, a molded counter and innersole upon a last preliminary to lasting, having, in combination, means for pressing the counter against the sides of the last at the sole edge, means for wiping the upper over the rear edge of the last, means constructed and arranged for securing the upper and counter to the innersole at the rear end of the last, and means for securing the flange of the counter only at points in advance of the overwiped upper and adjacent to the points of pressure.

43. An assembling machine having, in combination, automatic means for holding a flanged counter in position upon a last by pressure applied inwardly substantially in

the plane of the innersole, automatic means for thereafter securing the flange and upper to the innersole at one point, and means for securing the flange only to the innersole.

5 44. A machine for assembling an upper, a molded counter and innersole, having, in combination, means for adjusting relatively the upper, counter and sole, means for securing the upper and counter to the rear end 10 face of the last, and means for securing the flange of the counter to the sole at opposite sides of the sole.

45. A machine for securing in assembled relation upon a last, preliminary to lasting, an upper molded counter and innersole, having, in combination, means for pressing the upper materials including the counter against the rear end face of the last, means for pressing and holding the upper against 20 the sides of the last, and means for securing the flange of the counter to the heel seat at the rear part of the heel seat and inside the upstanding margin of the upper.

46. A machine for securing in assembled 25 relation upon a last, preliminary to lasting, an upper, molded counter and innersole, having, in combination, means for wiping the upper over the heel seat at the end of the heel seat, means for driving a tack in the 30 wiped over upper at the end of the heel seat, and tacking means arranged in advance of said tack driving means and adapted to pass beyond the portion of the upper wiped over by the wiping means and to insert tacks through the counter flange on 35 opposite sides of the shoe bottom.

47. A machine for securing in assembled 40 relation upon a last, preliminary to lasting, an upper, molded counter and innersole, having, in combination, means to insert a tack in the rear end face of the last, means for wiping over the upper at the rear end of the heel seat, means acting subsequently to said inserting means for securing the 45 wiped over upper to the heel seat, and means for simultaneously driving a plurality of tacks through the counter flange only at points where the upper is not wiped over the heel seat.

50 48. A machine for assembling, prelimi-

nary to lasting, an upper, molded counter and innersole loosely arranged upon a last, having, in combination, mechanism for driving a tack in the rear end of the last, means for wiping a portion of the upper over the heel seat at the end of the heel seat, means for tacking the wiped over portion of the upper, and means for simultaneously inserting another tack through the counter flange in such position as not to pass through the 60 upper.

49. A machine for securing an upper, counter and innersole in assembled relation on a last preparatory to the pulling-over and lasting operations, having, in combination, 65 means for simultaneously forcing inwardly the upper and counter at the corners of the last adjacent to the plane of the heel seat, and means for securing the flange of the counter at the two corners of the heel seat 70 only and adjacent to the points where the inwardly directed force is applied.

50. A machine for securing parts of boots and shoes in assembled relation upon a last preliminary to lasting having, in combination, 75 a back gage, means for effecting end-wise pressure of the last against the back gage to hold the upper and counter in close relation to the end of the last, means for holding in the counter at the sides of the heel portion by pressure applied locally at 80 separated points to the shoe, and automatic means for securing the margin of the counter to the innersole at points opposite to the points to which pressure has been applied. 85

51. A machine for assembling an upper, counter and innersole upon a last preliminary to lasting having, in combination, means for holding said shoe parts in assembled relation upon a last, and fastening 90 inserting means movable lengthwise of the last to secure the counter to the heel seat at a plurality of points upon opposite sides of the heel seat.

In testimony whereof I have signed my 95 name to this specification.

HANNAH ASHTON,
*Executrix of the will of Orrell Ashton,
deceased.*
